POINT CONTACT SEMICONDUCTOR UNIT

Robert A. Langevin, Wellesley, and Edmund A. Gschwind, Framingham, Mass., assignors to Clevite Corporation, Cleveland, Ohio, a corporation of Ohio

Application January 25, 1954, Serial No. 405,922

12 Claims. (Cl. 317—235)

This invention relates to a point contact semiconductor unit.

The basic configuration of the point contact transistor includes a semiconductor, a base electrode having an ohmic contact with one face of the semiconductor, and a pair of small wire or "cat whisker" emitter and collector electrodes having spaced rectifying point contacts with the opposite face of the semiconductor. To achieve the desired electrical characteristics with these transistors it is necessary to establish a precise predetermined spacing between the emitter and collector electrode contacts on the semiconductor, this spacing ordinarily being of the order of .002 inch to .008 inch. It is the common practice at present to establish this critical spacing between the emitter and collector electrode contacts through hand adjustment by human operators employing microscopes. This exacting hand operation is introduced at one of the most critical points in the fabrication of point contact transistors and hence must be performed with great care and skill, adding substantially to the cost of the finished articles.

Since proper operation of point contact transistors depends upon maintaining the emitter and collector electrodes in contact with the semiconductor, it is necessary to exert a force on these electrodes to insure that they stay in contact with the semiconductor when the latter undergoes small displacements due to thermal expansion and contraction or other causes. Various expedients have been adopted for this purpose, including the incorporation in the electrodes themselves of some sort of formed spring structure which acts to maintain contact pressure of the electrode against the semiconductor throughout such displacements. The formation of such spring structures presents formidable difficulties in view of the small electrode wire diameters, which may be as small as .003 inch, and the dissimilar materials of which the electrodes proper and the formed spring may be composed.

In addition, such point contact transistors in many cases require an impregnant for protecting the unit against moisture. At the same time this impregnant should allow the springs incorporated in the point contact electrodes to act, and in some instances the impregnant may mechanically damp these electrodes to some extent. The impregnant contacts the surface of the semiconductor and may be a source of contamination leading to defective operation and poor aging characteristics in the finished transistor.

It is the purpose of the present invention to provide a point contact semiconductor unit having novel provision for properly spacing the point contact electrodes, for stressing the electrodes to maintain the electrodes in contact with the semiconductor at all times, and for moisture proofing the unit, all without the difficulties and disadvantages associated with the prior art devices of this type.

It is, therefore, an object of this invention to provide a novel and improved point contact semiconductor unit.

A further object of the present invention is to provide

2

a novel point contact semiconductor unit having a novel arrangement for establishing and maintaining the proper spacing between the electrode point contacts on the semiconductor.

5 It is also an object of this invention to provide a novel point contact semiconductor unit having provision for stressing a point contact electrode in a novel and simplified manner to maintain it in proper contact with the semiconductor.

10 Another object of this invention is to provide a novel moisture resistant point contact semiconductor unit.

Still another object of this invention is to provide a novel arrangement which simplifies and economizes the fabrication of point contact semiconductor units.

In the preferred embodiments of the present invention, which is illustrated in the accompanying drawing and set forth in detail in the following description, the foregoing objects are accomplished by the provision of a semiconductor unit in which the semiconductor is received snugly within a housing, the housing being formed with passages leading to the semiconductor which receive the electrode wires and which are separated by a projection, the electrode wires being stressed to bear against this projection, so that their spacing at their respective 20 point contacts on the semiconductor is determined by the thickness of the projection, and also stressed to be maintained in contact with the semiconductor at all times.

In the drawing:

Figure 1 is an exploded perspective view of a point contact transistor unit in accordance with the present invention, with the point contact electrodes omitted for clarity;

Figure 2 is a perspective view showing the front housing section of the transistor unit;

Figure 3 is a front view of the unit, showing in dotted lines the manner in which the point contact electrodes are received in the housing and stressed to maintain contact with the semiconductor;

Figure 4 is a transverse section on a reduced scale centrally through the unit along the line 4—4 in Fig. 3; and

Figure 5 is a section along the line 5—5 in Fig. 3.

Referring to the drawing, in accordance with the preferred embodiment of the present invention there is provided a two-piece housing consisting of a rear section 10 and a smaller front section 11 adapted to be assembled in confronting relation with their respective inner, generally flat faces 12 and 13 abutting against one another. Each of these housing sections is molded of dielectric material which is substantially impervious to moisture. The rear housing section 10 is formed with a pair of integral dowels or studs 14 and 15 projecting forward from its inner face and adapted to be received snugly in complementary holes 16 and 17 extending through the front housing section 11. This arrangement facilitates the quick assembly together of the housing sections in the proper manner.

The housing sections 10 and 11 are formed with generally rectangular recesses or cavities 18 and 19 respectively which are open at the confronting inner faces of the housing sections and which are aligned in general registration with one another, so that they define a single chamber or compartment for receiving the semiconductor when the housing sections are assembled together. A base insert 21, preferably of Monel metal, is molded integral with the rear housing section 10. This base insert adjacent its forward end rests on the bottom wall of the recess 18 in the rear housing section 10. At its forward extremity the base insert 21 projects beyond the inner face 12 of the rear housing section 10 and is disposed in spaced relation above the bottom wall of the recess 19 in the front housing section 11, as best seen in Fig. 4. Behind the recess 18 the base

3

insert 21 extends completely through and beyond the rear housing section 10 for connection to an appropriate electrical terminal. In back of the housing recess 18 the base insert 21 is formed with a pair of holes 20a and 20b (Fig. 5) into which the material of the rear housing section flows when it is molded to anchor the base insert in place. 5

A wafer 25 of semiconductor material, such as germanium, is soldered to the upper face of base electrode 22, after which the base electrode 22 is spot welded 10 at its lower face to the upper face of the base insert 21. Thus, the base insert 21 serves as a lead-in conductor for the base electrode. The back edge 23 of base electrode 22 abuts against the back wall 24 of the recess 18 in the rear housing section 10, as best seen in Fig. 4. Thus, the base electrode locates the semiconductor wafer 25 at the desired position within the housing. Obviously, the base electrode 22 contacts the semiconductor 20 wafer 25 completely across the latter's bottom face, providing a large area, low resistance, ohmic contact thereat on the semiconductor.

For receiving the point contact electrodes the front housing section 11 is formed at its inner face with a pair of spaced passages 26 and 27 having the configuration shown in Figs. 2 and 3. These passages have relatively widely spaced openings each of which is relatively wide from front to back and from side to side at the top of the front housing section. Shortly below their upper ends these passages become relatively narrow from side to side, each with parallel side walls spaced apart from .012 to 0.18 inch down to the recess 19 in the front housing section 11. Also, as best seen in Fig. 4, the passages 26 and 27 each taper toward the inner face 13 of the front housing section 11 in a direction down from the upper ends of these passages and become narrow from front to back, with an even depth of from .008 to .012 inch down to the recess 19 in one practical embodiment. Passages 26 and 27 are separated by a spacer in the form of a wedge-shaped nose 28 which is relatively wide at its upper end and which tapers down to a thin segment 28a at its lower end immediately above the recess 19. This thin segment 28a at the lower end of nose 28 has parallel side faces spaced apart a distance substantially equal to the desired spacing between the electrode point contacts on the semiconductor, which in one practical embodiment may be from .0045 to .0055 inch. The outer sides of the passages 26 and 27 adjacent the upper ends of these passages are formed with curved shoulders 29 and 30, respectively, which converge toward each other in a direction down toward recess 19.

The lead-in conductors for the respective point contact electrodes are in the form of pins 33 and 34 of Monel metal which are molded into the rear housing section 10. These pins terminate at their forward ends just beyond the front face 12 of the rear housing section and extend rearwardly therefrom through and beyond the rear housing section. As shown in Fig. 4, each pin is formed with a knurled enlarged portion disposed within the rear housing section 10 for anchoring the pin in the molded body 10.

In the assembly of this unit, after the semiconductor 25 and its base electrode 22 have been properly spot welded to base insert 21 as shown in Fig. 1, with the base insert 21 adjacent its forward end resting on the bottom of recess 18 in the rear housing section, the rear edge 23 of base electrode 22 abutting against the back wall 24 of recess 18, and the semiconductor 25 soldered to the upper face of base electrode 22, the front housing section 11 is then positioned in confronting relation with the rear housing section, with the respective inner faces of the housing sections abutting against each other and the dowels 14 and 15 on the rear housing section received snugly in the openings 16 and 17 in the front housing section. When thus positioned, the housing sec-

tions are then welded together by means of a hot welding tool conventional to the plastic industry.

Then, a pair of point contact electrodes in the form of thin, flexible, resilient wires or "cat whiskers" 31 and 32 of tungsten, phosphor bronze, or other suitable material, and having a diameter of the order of .005 inch, are inserted from the top openings down into the passages 26 and 27 until their sharpened, bevel-edged lower ends engage the upper face of the germanium wafer 25. The point contact electrode wires thus have rectifying, high resistance contacts on the semiconductor. These wires are then spread apart at their upper ends until they overlie the forward ends of the lead in conductors 33 and 34. This causes the point contact electrode wires to bear against the curved shoulders 29 and 30 adjacent the upper ends of the passages 26 and 27, as shown in Fig. 3. This, in turn, stresses the wires so that adjacent their lower ends they bear tightly against the parallel opposite sides of the thin nose segment 28a at the inner face of the front housing member 11. Since their sharpened edges are in mutually adjacent relationship, the point contacts of the electrode wires on the semiconductor are spaced apart by the thickness of the lower segment 28a of the nose 28. With the point contact electrode wires stressed in this manner they are then spot welded to the front ends of the lead-in conductors 33 and 34. From Fig. 3 it will be apparent that the connections of the point contact electrode wires 26 and 27 to the lead-in conductors 33 and 34 maintain the electrode wires spread apart at their upper ends and deformed, as described. This deformation of the normally straight point contact electrode wires stresses them so that at their lower ends they conform tightly against the lower segment 28a of the nose 28 and thereby have a spacing at their point contacts on the germanium wafer determined by the thickness of the thin nose segment 28a. The stressing of the point contact electrode wires in this manner also imparts to each of them a downward component of force which maintains each in intimate contact with the germanium wafer throughout any dimensional changes in the latter due to thermal expansion or the like. Before insertion into the housing the electrode wires 31 and 32 may be either straight or else preformed to a particular shape, not straight, so that they are stressed in the desired manner, by being mounted as described, to exert suitable forces against the housing nose 28 and against the semiconductor 25. This preforming of the electrode wires may either add to or subtract from the stresses imposed on the electrode wires by being assembled in the housing as described.

If desired, the upper ends of the electrode wires 26, 27 may be bent over to lie flat across the top of the rear housing section 19, as indicated in Figs. 3 and 4.

The transistor unit may then be finished by inserting it into a mold cavity somewhat larger than the unit itself and filling the mold cavity with a suitable moisture-resistant plastic, which coats the outside of the housing about $\frac{1}{16}$ inch thick and completely seals the unit against moisture. While the plastic seals the outer ends of the passages 26, 27, as well as any other openings in the housing assembly, it does not flow down into the housing chamber to contaminate the semiconductor 25 because the narrow passages 26, 27 do not permit the escape of air in these passages and in the housing chamber 18, 19 for the semiconductor. In one practical embodiment, the passages 26, 27 are each .012 inch to .018 inch across and .008 inch to .012 inch deep. Since the electrode wires themselves are .003 inch or larger in diameter, the opening through each passage 26, 27 down into the housing chamber 18, 19 for the semiconductor is insufficient to permit the escape of the trapped air so that the waterproofing plastic might flow down into the chamber to contact the semiconductor. Therefore, this provision for waterproofing the semiconductor unit does not result in contamination of the semiconductor.

From the foregoing it will be apparent that the objects and purposes of the present invention are accomplished in an advantageous manner by the specific arrangement described above. However, it should be evident that the principles of the present invention may be incorporated into assemblies differing from the specific embodiment described above and illustrated in the accompanying drawing, as, for example, in point contact semiconductor devices differing from the standard transistor included in the above-described unit. Therefore, while in the foregoing description and the accompanying drawing there has been disclosed a specific preferred embodiment of the present invention, it is to be understood that various modifications, omissions and refinements which depart from the specific disclosed embodiment may be adopted without departing from the spirit and scope of this invention.

We claim:

1. A point contact semiconductor unit comprising a semiconductor, a pair of flexible, resilient electrode wires each having point contact with the semiconductor, a housing defining a chamber receiving the semiconductor and formed with spaced passages extending into the chamber and receiving the point contact electrode wires, said passages being separated by a spacer, said electrode wires beyond said passages being spread apart greater than the spacing between the passages immediately adjacent said chamber, and said electrode wires beyond said passages being secured to lead-in conductors and thereby stressed to bear against said spacer immediately adjacent the chamber to have a spacing at the semiconductor determined by the spacer.

2. In a point contact semiconductor unit, the combination of a semiconductor, a two-piece housing including a first housing section formed with a recess open at its inner face and a second housing section having its inner face abutting against the inner face of the second housing section, said second housing section being formed with a recess open at its inner face and communicating with said recess in the first housing section and defining therewith a chamber receiving the semiconductor, one of said housing sections at its inner face being formed with a pair of channels communicating with said chamber and separated by a spacer integral with said housing section, said spacer immediately adjacent said chamber having closely spaced side walls at the channels which extend parallel to each other, said spacer in a direction away from said chamber becoming progressively thicker with its side walls at the channels diverging away from each other, a pair of flexible, resilient electrode wires extending through said channels and having point contacts on the semiconductor in said chamber, and means stressing said electrode wires to force them against the spacer at said parallel side walls immediately adjacent said chamber so that the electrodes at their point contacts on the semiconductor are spaced apart a distance corresponding to the thickness of the spacer between said parallel side walls and stressing said electrode wires to press them against the semiconductor.

3. In a point contact semiconductor unit, the combination of a semiconductor, a two-piece housing including a pair of housing sections having abutting inner faces and formed with communicating recesses thereat which define a chamber receiving the semiconductor, one of said housing sections at its inner face being formed with a pair of channels communicating with said chamber and separated by a spacer integral with said housing section, said spacer immediately adjacent said chamber having closely spaced, parallel side walls at the respective channels, said channels being formed with outer side walls disposed opposite the respective side walls of the spacer and in a direction away from said chamber diverging away from each other, a pair of flexible, resilient electrode wires extending through said channels and having point contacts on the semiconductor, said electrode wires beyond said channels in a direction away from said chamber being spread apart a distance greater than the spacing between the channels

at their outer ends and secured fixedly thereto to stress said electrode wires against said outer side walls of the channels and thereby deform said electrode wires to bear against said parallel side walls of the spacer immediately adjacent said chamber to have a spacing at their respective point contacts on the semiconductor equal to the spacing between said parallel side walls of the spacer and to stress said electrode wires to bear against the semiconductor.

10 4. The combination of claim 3, wherein said electrode wires are each normally straight.

5. The combination of claim 3, wherein said electrode wires are each preformed to modify the forces exerted on the electrode wires by their respective mountings on the housing.

6. In a point contact semiconductor unit, the combination of a housing having a chamber, a semiconductor in said chamber, said housing having a pair of adjacent passages leading into said chamber, and a pair of flexible resilient electrode wires narrower than said passages and extending through said passages into said chamber and engaging the semiconductor in point contact fashion, said electrode wires being mounted on said housing to be stressed to bear against the semiconductor at their respective point contacts therewith and to bear against the adjacent walls of the passages adjacent said chamber to have a spacing at their point contacts on the semiconductor determined by the spacing between said adjacent walls of the passages adjacent said chamber.

30 7. In a point contact semiconductor unit, the combination of a housing having a chamber, a semiconductor in said chamber, said housing having a passage leading into said chamber, a flexible resilient electrode wire narrower than said passage and extending through said passage into said chamber and engaging the semiconductor in point contact fashion, and means beyond said passage stressing said electrode wire to bear against a side wall of said passage immediately adjacent the chamber so that the position of the contact point of the electrode wire on the semiconductor is determined by the position of said passage side wall.

45 8. In a point contact semiconductor unit, the combination of a housing having a chamber, a semiconductor in said chamber, said housing having a passage leading into said chamber, and a flexible resilient electrode wire extending through said passage into said chamber and engaging the semiconductor in point contact fashion, said electrode wire being mounted on the housing outside said passage to be deformed in said passage to exert contact pressure on the semiconductor.

50 9. In a point contact semiconductor unit, the combination of a housing containing a chamber, a semiconductor in said chamber, said housing having a passage leading from outside the housing into said chamber, and a flexible resilient electrode wire narrower than said passage and extending through said passage into said chamber and having point contact with the semiconductor, said electrode being secured fixedly beyond said passage and stressed to bear against one wall of the passage adjacent the end of the passage remote from said chamber and bearing against the opposite side wall of the passage immediately adjacent the chamber so that the position of the electrode wire at its point contact on the semiconductor is determined by said opposite passage side wall.

65 10. In a point contact transistor unit, the combination of a pair of housing members abutting at their inner faces and formed with communicating recesses thereat defining a chamber, a base insert molded into one of said housing members and extending therethrough into said chamber, a base electrode secured to said base insert and received in said chamber with one of its side edges abutting against a wall of said chamber to locate the base electrode properly within said chamber, a semiconductor disposed in said chamber and secured at one of its faces to the base

7
electrode, and a pair of electrodes having point contact with the opposite face of the semiconductor.

11. A point contact transistor unit comprising a two-piece housing including a pair of housing sections having abutting inner faces and formed with communicating recesses thereat which define a chamber for receiving a semiconductor, a base insert molded into one of said housing sections and extending therethrough into said chamber, a base electrode secured to said base insert and received in said chamber with one of its side edges abutting against one wall of said chamber to position said base electrode properly within said chamber, a semiconductor disposed in said chamber and secured at one of its faces to the base electrode, one of said housing sections at its inner face being formed with a pair of channels communicating with said chamber and separated by a spacer integral with said housing section, said spacer immediately adjacent said chamber having closely spaced, parallel side walls at the respective channels, said channels being formed with outer side walls opposite the respective side walls of the spacer which diverge away from each other in a direction away from said chamber, a pair of flexible, resilient, electrode wires extending through said channels and having point contacts on the semiconductor, said electrode wires beyond said channels in a direction 25 away from said chamber being spread apart a distance greater than the spacing between the channels at their outer ends and secured fixedly thereto to stress said electrode wires against said outer side walls of the channels and thereby to deform said electrode wires to bear 30 against said parallel side walls of the spacer immediately

5 adjacent said chamber to have a spacing at their respective point contacts on the semiconductor equal to the spacing between said parallel side walls of the spacer and to stress said electrode wires to bear against the semiconductor.

12. A point contact transistor unit comprising a housing of moisture-resistant material, said housing having an internal chamber, a base insert molded into said housing and extending from outside the housing into said 10 chamber therein, a base electrode secured to said base insert within said housing chamber, a semiconductor secured at one of its faces to said base electrode, said housing being formed with a pair of spaced narrow passages leading from outside the housing into said chamber at the opposite face of the semiconductor, a pair of electrode wires extending from outside the housing through said passages into said housing chamber and each having point contact with said opposite face of the semiconductor at spaced locations thereon, and a coating 15 of moisture-resistant plastic molded around the housing and rendering the unit substantially moisture proof.
